UNITED STATES PATENT OFFICE

172,257

CONCRETE POST FOR CHAIN LINK FENCE

Purl J. Vickers, Houston, Tex.

Application October 30, 1952, Serial No. 22,047

Term of patent 14 years

(Cl. D28—1)

To all whom it may concern:

Be it known that I, Purl J. Vickers, a citizen of the United States, residing at Houston, in the county of Harris, State of Texas, have invented a new, original, and ornamental Design for Concrete Post for Chain Link Fence, of which the following is a specification, reference being had to the accompanying drawings, forming a part hereof.

Figure 1 is an elevational view of a concrete post for chain link fence showing my new design;

Figure 2 is a top plan view; and

Figure 3 is an isometric view upon an enlarged

scale of the upper portion of the fence post shown in the other views.

I claim:

The ornamental design for a concrete post for chain link fence, substantially as shown.
